Int. Cl. D9—03

U.S. Cl. D9—245

The figure is a plan view of an end cap blank for a shipping package embodying my new design, the opposite side being substantially a mirror image thereof.

The blank is of conventional thickness and the dash lines represent fold lines.

This is a division of application Ser. No. D. 449,923, filed Mar. 11, 1974.

I claim:

The ornamental design for an end cap blank for a shipping package, substantially as shown and described.
